HERBERT L. KIMMELL, OF LOS ANGELES, CALIFORNIA, ASSIGNOR, BY MESNE ASSIGNMENTS, TO W. F. BIANCHI TOMPKINS, OF NEW YORK, N. Y.

CARBURETER.

1,156,084.

Specification of Letters Patent. Patented Oct. 12, 1915.

Application filed February 20, 1908. Serial No. 416,916.

To all whom it may concern:

Be it known that I, HERBERT L. KIMMELL, a citizen of the United States, residing at Los Angeles, in the county of Los Angeles 5 and State of California, have invented a new and useful Carbureter, of which the following is a specification.

This invention relates to carbureters, and the main object of the invention is to provide 10 for furnishing a perfect mixture of gas and air under all conditions of speed and atmosphere, and to deliver a substantially uniform amount to each cylinder. The latter feature is of considerable importance for, as is 15 well known, in a multi-cylinder engine the suction will vary in the different cylinders and when a cylinder having good suction takes its charge from the carbureter, if the latter is of ordinary type, the next cylinder 20 in succession having a weaker suction is unable to get its quota of mixture as the previous cylinder has depleted the supply.

Another object is to eliminate the usual 25 automatic air inlet valve and to provide for positively regulating the size of the air inlet to correspond to the oil inlet or needle valve opening.

Another object is to enable the device to be easily adjusted without removing it from 30 the engine.

Referring to the drawings, Figure 1 is a vertical sectional view through the device, the view being taken on line x^1-x^1 Fig. 2. Fig. 2 is a plan view. Fig. 3 is a section on line x^3-x^3 Fig. 2. Fig. 4 is a section on line x^4-x^4 Fig. 2. Fig. 5 is an end elevation of the air valve.

1 designates a float valve chamber in which is a float valve 2 operating a rock-arm 40 3 pivoted at 4 and having an arm 5 which engages in a groove 6 in an automatic oil inlet valve 7, the lower end of which is tapered to co-act with a valve seat 8 formed in a nipple 9 which is screwed into the 45 lower end of the side casing 10 and the nipple has a central bore 11 through which the oil is fed. The upper end of the valve 7 slides in a plug 12 which is screwed in the upper end of the casing 10. Oil enters 50 through nipple 9 and flows past the valve 7 into the float valve chamber 1 and rises to the level indicated causing the float 2 to rise which moves down valve 7 against valve

seat 8 and shuts off further supply of oil. As oil is removed from the chamber 1 the 55 float 2 descends and lifts valve 7, thereby permitting oil to again flow into chamber 1 and replenish the same; thus the float 2 and valve 7 automatically operate to maintain a substantially constant level of oil in the 60 chamber 1. In this connection it should be noted that the closing movement of the valve 7 is downward and the valve 7 is located above the valve seat 8. This gives an unobstructed flow of the oil past the valve 65 seat and dispenses with a stuffing box below the valve seat thereby avoiding leakage. From the chamber 1 the oil flows through a passage 13 to a valve chamber 14 in which is a set valve 15, the lower end of the set 70 valve 15 being screwed in an extension 16 of the chamber 14, a stuffing box 17 being employed to prevent leakage. At the upper end of the valve chamber 14 is a valve seat 18 which co-acts with set valve 15 to regulate the passage of oil into the superimposed mixing chamber 19. The set valve 15 is always open and should be adjusted so that a sufficient amount of oil will flow by gravity 75 past the valve seat 18 into the mixing chamber 19 to start the engine, but, as will be later explained the set valve 15 does not furnish oil for the regular running of the engine after it has been started, the oil for 80 regular running being admitted through a valve seat 20 which is also located at the top of the valve chamber 14. The level of the valve seat 20 is below the level of the valve seat 18 for a purpose to be described.

The valve seat 20 is controlled by a gasoline valve 21 the stem of which is threaded in a sleeve 22, the valve 21 being adjustable in the sleeve 22 but it does not turn normally therein, being locked in its regulated position in the sleeve by a stuffing box 23, the 85 latter serving the double function as stuffing box and locking means. By loosening the stuffing box 23 the gasoline valve 21 may be adjusted by screwing it up or down in the sleeve 22. The sleeve 22 is provided externally with relatively coarse threads and is screwed into a projection 24 of the casing 90 25 which incloses the mixing chamber 19. A slotted rock-arm 26 is provided with a split hub 27 which is clamped to the sleeve 22 and 100 105 by operating the rock-arm 26 the sleeve may

be turned and at the same time moved longitudinally by its threaded portion thereby imparting a longitudinal movement to the valve 21 causing the valve to advance or 5 recede from its seat 20, according to the direction in which the sleeve is turned.

An intermediate air chamber 28 is located below the mixing chamber 19 and is closed to the atmosphere except by an air inlet 10 opening 29. At its upper end the chamber 28 communicates with the mixing chamber 19. Slidable within the casing 25 which forms the mixing chamber is an air valve 30 which comprises a shell having two wide 15 slots 31 and 32 and one narrow slot 33, the slot 32 extending through nearly the entire length of the shell, being formed to maintain constant communication between the mixing chamber 19 and valve seats 18 and 20 and air chamber 28 irrespective of the 20 position in which the shell 30 may be. The slot 33 is formed to give room for the valve 21 and allow full movement for the air valve 30 as the latter extends diametrically 25 through the valve 30. The slot 31 is extended back only part way from the top of the shell and when the valve 30 is closed the slot 31 does not fully meet the end wall 30 of the passage 34 and the passage 34 is thus left open for a narrow space, as shown in Fig. 4, to permit of the passage of a limited amount of gas and air therethrough in starting the engine. At this time the oil which 35 enters the mixture chamber enters by gravity past the set valve 15 as the gasoline valve 21 is closed and the air for the mixture enters through the opening 29 into the air chamber 28 thus entering the mixing chamber 19 where it combines with the oil 40 therein and the mixture enters through the narrow slot in passage 34 into the reservoir chamber 35 which is located above the float valve chamber 1. From the reservoir chamber 35 the mixture enters the induction pipes, not shown, by which it is conducted 45 to the cylinder or cylinders.

After the engine has been started, the main gasoline valve 21 is raised from its seat 20 to admit more gasoline, and at the same time 50 the air valve 30 is moved to a corresponding extent to admit air to produce the requisite mixture. Gasoline now enters the mixing chamber 19 almost entirely through the seat 20, and only a small amount will enter 55 through the seat 18, although open to the same extent as before. The reason is that suction applied to a fluid at one end of a conduit is increased or diminished at the other end thereof according as the first end is 60 greater or less than the second and approximately in the same ratio. Thus, if the area of the annular passage between the conical end of the valve 21 and its conical seat 20 be four times as great at the top as at the 65 bottom, the suction will be increased at the

bottom of said passage approximately in the ratio 1 to 4. Conversely, under similar but reversed conditions, the suction at the top of the annular conduit between the valve 15 and its seat 18 will be decreased approximately in the proportion 4 to 1. Thus, although the levels of the fluids at the two valve seats are the same and said valves are opened to the same extent, the suction of the engine will be 16 times as effective on 70 the gasoline at the valve seat 20 as at the valve seat 18.

By the above-described arrangement the engine may be started with the main gasoline valve 21 practically closed, so that the 80 engine does not race immediately after starting. Also, since a given volume of mixture will enter the engine at a fixed position of the throttle, regardless of the momentum of the engine, the engine will not race when 85 the clutch is released.

A link 36 is adjustably attached by a bolt 36' to slotted arm 26 and the other end of link 36 passes slidably through a block 37 which is pivoted to an arm 38, the arm 38 90 being attached to a stem 39, the stem 39 passing through the end of the mixing chamber casing 25 and being attached to the valve 30. The link 36 has a head 40 which bears against the block 37 and a coil spring 41 95 is mounted on the other side of the block and is fastened to the link 36 and tends to retract the link 36 to hold its head 40 against block 37, yet it permits the air valve stem 39 to be pushed in, block 37 sliding until 100 link 36 compresses spring 41, after the link 36 has moved the slotted arm 26 into such position that the gasoline valve 21 is closed. Thus, after the gasoline valve has been closed, outward movement of the valve 30 105 will not cause a similar outward movement of link 36 and lifting of throttle valve 21, until block 37 strikes the head 40 of link 36.

The casing 25 is formed with an air inlet opening 42, which is opened by the movement of the valve 30 in the direction corresponding to the opening movement of the valve 21. By adjusting the link 36 on the slotted arm 26, the desired ratio of opening and closing movement between the valve 21 115 and the opening and closing of the air inlet 42, may be secured. A very important feature of my invention resides in the form of this opening 42, by which there is obtained a proper mixture of air and gasoline vapor at whatever rate they are supplied to the engine. So far as I am aware, in all prior forms of carburetors in which an auxiliary air supply is automatically increased with the gasoline supply, the air inlet opening 120 thereof has been increased at the same ratio as the gasoline inlet opening. But by reason of the increased speed of the engine when more gasoline is supplied thereto, not only is the suction greater on the surface of 125

the gasoline at the main gasoline valve, but on the surrounding air drawn from the chamber 28, and which is used to spray said gasoline. Hence more gasoline is supplied 5 to the engine than would result merely from the increase size of the gasoline inlet. I provide for this increased gasoline supply by forming the inlet opening 42 triangular, or with divergent sides, as shown, so that a 10 substantially perfect mixture is obtained at all positions of the main gasoline valve. I thus dispense with the use of a spring to oppose the opening of the air valve. Since such springs have to be overcome by the outside atmospheric pressure, they reduce the 15 effective atmospheric pressure by the force of the spring which is required to be overcome. The reduction in the effective pressure causes incompleteness of the filling of 20 the cylinder with mixture, thus correspondingly reducing the effectiveness of the engine.

What I claim is:—

1. In a carbureter, the combination of a float chamber, a float therein, a valve controlled 25 by the float for regulating the admission of gasoline to the float chamber, a cylindrical horizontal mixing chamber at one side of the float chamber, a gas chamber supported above the float chamber and in connection 30 with the mixing chamber, a gasoline passage from the float chamber to the mixing chamber, means to control the admission of air to the mixing chamber, a sleeve threaded in the casing of the mixing chamber, a gasoline 35 valve to control said passage screwed in said sleeve, an arm clamped to the sleeve to move the same, and a link adjustably attached to said arm, said link being also connected to said air controlling means and permitting 40 limited relative movement of said means and said gasoline valve.

2. In a carbureter, the combination of a float chamber, a float therein, a valve controlled by the float for regulating the admission 45 of gasoline to the float chamber, a cylindrical mixing chamber, supported on one side of the float chamber and having an air admission port, a gas chamber supported above the float chamber and in communication 50 with the mixing chamber, a gasoline passage from the float chamber to the mixing chamber, an adjustable set valve in said passage for controlling the flow of gasoline therethrough, a second passage from the 55 float chamber to the mixing chamber, a gasoline valve freely movable for varying the flow of gasoline therethrough, a valve for controlling the air admission port, said valve also controlling the flow of mixture to said 60 reservoir, and means connecting the air valve stem to the last named gasoline valve for moving the two simultaneously, said means including a spring to permit relative movement of the valves.

3. In a carbureter, the combination of a

cylindrical mixing chamber, a float chamber at one side of and communicating with the mixing chamber, a gas chamber above and supported on the float chamber, a longitudinally movable sleeve valve to control the admission of carbureted air from the mixing chamber to the gas chamber, an inlet port disposed in the underside of the mixing chamber and a needle valve having its stem extending above the outside of the mixing 70 chamber, the valve coöperating with the inlet port to regulate the admission of gasoline from the float chamber to the mixing chamber, said sleeve valve being slotted longitudinally to straddle the needle valve.

4. In a carbureter, the combination of a mixing chamber having an air inlet port, a longitudinally movable sleeve-like air valve disposed within the mixing chamber to control the opening of the air port, a gasoline 85 chamber communicating with the mixing chamber, a needle valve to regulate the admission of gasoline from the gasoline chamber to the mixing chamber, an externally 90 screw threaded sleeve mounted in the shell of the mixing chamber and supporting the needle valve, an arm secured to said screw threaded sleeve, and a link connection between said arm and the stem of the sleeve-like air valve, said arm being slotted longitudinally to permit the connection of the link to the arm to be moved toward or from the axis of the threaded sleeve.

5. In a carbureter, the combination of a cylindrical mixing chamber having an air 100 inlet port and a gasoline inlet port, a gas chamber integral with the mixing chamber and having a flat underside, a gasoline chamber fitting against the underside of the gas chamber, a conduit to conduct the gasoline 105 from the gasoline chamber to the mixing chamber, a valve to regulate the flow of gasoline to the mixing chamber and a longitudinally movable sleeve valve to regulate the admission of air to the mixing chamber.

6. In a carbureter, the combination of a mixing chamber having a port for the admission of gasoline, a valve to regulate the admission of gasoline to the mixing chamber, an externally threaded sleeve mounted in 115 the wall of the mixing chamber and supporting the said valve, a sliding air valve in said mixing chamber and having a valve stem extended through the end of the mixing chamber, an arm on said threaded sleeve, an arm 120 on said valve stem and a link pivotally connected to the arm on said sleeve and having a sliding engagement with the arm on said spindle and a spring mounted on said link and bearing against the arm on the 125 spindle.

7. In a carbureter, the combination of a float chamber, a float therein, a gas chamber, a mixing chamber in communication with the gas chamber, a single duct for gaso- 130

lene leading from the float chamber to the mixing chamber, and two valve controlled passages at the outer end of the duct for controlling the flow of gasoline from said duct to the mixing chamber, one of said valves being normally open and having a higher valve seat than the other.

In testimony whereof, I have hereunto set my hand at Los Angeles, California, this 13th day of February 1908.

HERBERT L. KIMMELL.

In presence of—

GEORGE T. HACKLEY,

FRANK L. A. GRAHAM.

Copies of this patent may be obtained for five cents each, by addressing the "Commissioner of Patents, Washington, D. C."

It is hereby certified that the name of the assignee in Letters Patent No. 1,156,084, granted October 12, 1915, upon the application of Herbert L. Kimmell, of Los Angeles, California, for an improvement in "Carbureters," was erroneously written and printed as "W. F. Bianchi Tompkins," whereas said name should have been written and printed as *F. Bianchi Tompkins*; and that the said Letters Patent should be read with this correction therein that the same may conform to the record of the case in the Patent Office.

Signed and sealed this 18th day of January, A. D., 1916.

[SEAL.]

J. T. NEWTON,

Acting Commissioner of Patents.
